Albin E. Johnson, San Gabriel, Calif.

Application November 9, 1948, Serial No. 149,546

Term of patent 14 years

(CL. D74—1)

To all whom it may concern:

Be it known that I, Albin E. Johnson, a citizen of the United States, residing at San Gabriel, California, in the county of Los Angeles and State of California, have invented a new, original, and ornamental Design for a Combination Carbon Paper and Stationery Cabinet, of which the following is a specification, reference being had to the accompanying drawings, forming part thereof.

Fig. 1 is a side view of a combination carbon paper and stationery cabinet, showing my new design;

Fig. 2 is an end view of Fig. 1;

Fig. 3 is a top plan view of Fig. 1;

Fig. 4 is a perspective view of Fig. 1, and,

Fig. 5 is a perspective view thereof in open position.

I claim:

The ornamental design for a combination carbon paper and stationery cabinet, as shown.

ALBIN E. JOHNSON.
